UNITED STATES PATENT OFFICE.

WILLIAM MARIN, OF NEW YORK, N. Y.

BRACKET.

1,227,165.

Specification of Letters Patent. Patented May 22, 1917.

Application filed September 24, 1915. Serial No. 52,476.

To all whom it may concern:

Be it known that I, WILLIAM MARIN, a subject of the Czar of Russia, residing at New York city, in the county of New York and State of New York, have invented new and useful Improvements in Brackets, of which the following is a specification.

This invention relates to brackets, and particularly to a bracket which is designed especially for the purpose of supporting flush tanks or the like, and it has for its object the provision of a device of this character which may be quickly applied to the wall or like support, and positioned thereon so as to readily receive the flush tank and effectually hold the same in an effective and secured position.

Another object of the invention is the provision of a supporting bracket for flush tanks which will be designed for the purpose of expediting the process of alining the tank on the application of the same to its support.

A still further object of the invention is the provision of a supporting bracket which will operate to secure the tank in an applied position without the necessity of materially injuring the tank.

Other objects will appear and be better understood from that embodiment of my invention of which the following is a specification, reference being had to the accompanying drawing forming part hereof, in which:

Figure 1 is a perspective view showing the application of the tank to a set of brackets.

Fig. 2 is a perspective view of the bracket.

Fig. 3 is a vertical longitudinal section therethrough showing a slightly modified form of the invention.

Fig. 4 is a side view of a portion of the bracket showing a still further modified form thereof.

Fig. 5 is a perspective view of the bracket showing another modified form thereof.

On reference to Figs. 1 and 2, it is seen that the bracket consists of a metal bar 1 preferably of uniform thickness throughout. At the extreme upper end the bar is cut. At the extreme upper end the bar is provided with a substantially key-hole shaped slot 2 which is adapted to receive a suitable fastening device 3 as shown in Fig. 1. At other suitable points in the length of the bar are formed passages 4 which are adapted to receive other or additional fastening devices 5. At the upper end and

preferably at a point adjacent to the key-hole slot 2 the bracket is provided with a member 6 or clamping device which is provided with a short angular extension 7 secured by a rivet or the like 8, to the bar 1, and as illustrated, said clamping device is offset at 9 and then extended in a downward direction and in diverging relation to the bar 1 to form a retaining flange 10, the extremity 11 of which being curved outwardly and away from the bar 1. At the lower end the bar 1 is upstruck so as to form a horizontal rest 12 having a passage 13 therein.

In use at least two of the brackets are employed for the purpose of properly supporting the flush tank. The clamping devices 6 may be swung into the dotted line position shown in Fig. 1, and the tank may be placed onto the horizontally alined rest 12, after which the clamping devices may be again swung or adjusted to their normal full line positions so that the offset portions 9 thereof come over the upper edge of the back wall of the tank. The flanges 10 will be extended down against the inner face of said rear wall, and the convexities of the extremities 11 will be brought into effective impinging engagement with said wall so as to hold the latter uniformly in close contact with the bar 1. The bottom of the tank, as stated, is designed to rest upon the alined portions 12 and after the tank has been applied in the manner above stated, permanency in its application may be effected by passing small fastening devices 14 through the passages 13 and into the bottom of the tank.

In the form shown in Fig. 3 the bar 1^a is provided near its upper end with a slot 15 which receives a clamping bolt 16. This bolt is connected with the extension 7^a of the clamping device 6^a. In this manner the clamping device, aside from being capable of slight rocking movements is also free to be adjusted in a vertical direction so that it may accommodate tanks of a given size.

In the form shown in Fig. 4 the bar 1^b has its clamping device 6^b formed as an integral part of the bar. It is extended into the bar through an offset continuation 17 thereof.

In the form shown in Fig. 5 the bar 1^c is upset upon itself at its upper end so as to form a flange 7^c of a clamping device 6^c; the latter being otherwise the same as the device described in the previously referred forms of the invention. Below the key-hole slot 18

a rivet 19 is passed through the bar 1^c and through the portion 7^e as illustrated. In either of the forms shown in Figs. 4 and 5, the upper edge of the tank may be accommodated by simply canting or tilting the tank at the time of adjusting the same to companion brackets as will be understood.

What is claimed as new is:

- 10 A bracket for flushing tanks comprising a bar provided with a rigid angular rest to support the base of the tank, a clamp pivoted at the opposite end of the bar for swinging movement parallel with the bar and at a right angle to the rest and adapted to be

extended over the rear wall of the tank and 15 provided with a flange adapted to come against the inner surface of the rear wall so as to hold the latter in contact with the bar approximately throughout the length thereof, said clamp being adjustable longitudinally of the bar and means for holding the clamp at an adjusted position on the bar. 20

In testimony whereof I affix my signature in presence of two witnesses.

WILLIAM MARIN.
